Patented Mar. 17, 1914.

UNITED STATES PATENT OFFICE.

GUSTAF H. STARCK, OF WAUKESHA, ILLINOIS.

APPARATUS FOR TREATING WASTE HYDROCHLORIC-ACID-PICKLE LIQUORS.

1,090,173.

Specification of Letters Patent. Patented Mar. 17, 1914.

Application filed July 3, 1912. Serial No. 797,493.

To all whom it may concern:

Be it known that I, GUSTAF H. STARCK, a citizen of the United States, residing at Waukesha, in the county of Lake and State of Illinois, have invented a certain new and useful Improvement in Apparatus for Treating Waste Hydrochloric-Acid-Pickle Liquors, of which the following is a specification.

10 In the process of galvanizing metallic articles such, for instance, as sheet metal, wire, and pipes, the articles to be galvanized are inserted in a tank or other receptacle containing hydrochloric acid, for the purpose of cleaning the surface of the article before it is galvanized. When iron is thus subjected to the influence of hydrochloric acid, a chemical action takes place, forming iron chlorids; not capable of cleaning the 15 iron surface. In other words, as successive articles are thus treated by the hydrochloric acid, the solution or "pickle" becomes weaker and weaker until finally so much of the strength of the hydrochloric acid is gone 20 that the operation cannot be further efficiently continued, and at the same time a deposit of solid material containing or carrying one or both of said chlorids is formed in the bottom of the acid tank. The solid 25 material just referred to can, if dried and properly treated, be used as the basis for a very satisfactory paint.

The object of this invention is to provide a plant of neat and compact form, which 30 can be readily installed and operated, which will subdivide the above mentioned iron chlorids into hydrochloric acid so that it can be used over again, and at the same time recover a paint pigment as a by-product 35 without any additional cost.

The invention consists in a plant capable of carrying out the foregoing objects, which possesses the general and specific features and details of construction hereinafter described in the specification and claims.

In the drawings, Figure 1 is a sectional side view of a plant illustrating this invention in its preferred form. Fig. 2 is a sectional detail view of the top and cover for 40 a washing cylinder. Fig. 3 is an enlarged detail sectional view of the feed end of the receptacle in which solid paint material is dried.

At one end of the plant are placed a plurality of fire boxes 10 having grates 12, the respective grates and fire boxes being

bounded by suitable walls as 14, 15 and 16. Any number of such grates may be provided, depending upon the size of the plant installed. Directly above these grates 12, so 50 that the fire built thereon may readily contact it, is placed one or more retorts 18 supported at one end on any suitable support, as iron rod 20, and at the other end in the end wall 14. This retort 18 may be of any 55 suitable cross section; in the preferred form of construction a circular pipe is used, a plurality of them being placed one beyond the other in a horizontal plane, as viewed in Fig. 1, so that only one is seen in the drawings. Both ends of this retort 18 are open, the left hand end being partially closed by a perforated plate or chamber 22, through which the outer air may pass into the receptacle 18. The right hand end opens into 60 a large passageway 24 which leads through the grates 12 over an ordinary puddling furnace, bath or hearth 26, and thence into the discharge passageway 28, 29, 30, 31, 32, and 33. Adjacent to the passageway 28, 65 just referred to, is what is called in the trade a "pickle tank" 34, supported upon any suitable standard at a sufficient height so that the spout 35 leading from this tank, and controlled by valve 36, enters the removable box 36 of a filter 37, mounted on a suitable support so that its spout 38, controlled by valve 39, enters passageway 28 70 at a sufficient height above the furnace so that the filtered "pickle" may drop or 75 trickle into the hearth 26, where it is heated by the flames coming from the fire upon the grates 12 and evaporated so that it passes through the delivery pipe 28, 30, 32, as heretofore described. The filter box 36 80 is fitted into a frame with a handle 40 so as to be conveniently lifted off and cleaned, the solid residue left therein being used in the paint tubes 18.

The reason for having two "pickle" receptacles 34 and 36 is that when the acid tanks are emptied (or drawn off), a considerable quantity of solid substance always follows with the liquid. If this is allowed to drip into the hearth 26, this solid substance will be spoiled for paint pigment purposes inasmuch as it will be mixed with ashes, and other non-combustible substances.

The end 33 of the delivery pipe just described, discharges into a vertical cylinder 42 normally about twenty feet high, which is connected at its top to a downwardly in-

clined pipe 43 which enters the bottom of another vertical cylinder 44 having at its top a discharge opening 46. The top of each one of these cylinders 42, 44, is closed by a plate 48 having an upwardly turned flange 50 forming a dish whose bottom is the plate 48. On the top of the plate 48 are a plurality of lugs 52. Through the plate 48 and each lug 52 thereon is a downwardly pointing 10 ed tapering hole 54. These holes are pref- erably made one-eighth of an inch in diameter at the bottom and three-sixteenths of an inch in diameter at the top, the thickness of the plate 48 being about one-half inch.

15 Suitably mounted upon the tops 48 of the cylinders 42 and 44 are the discharge ends 56 of a water pipe 58 connected by pipe 60 to any suitable source of supply. Water passing through this pipe 60 discharges through ends 56 into the interior of the dish 48—50 and thence passes through the opening 54 down into the cylinders 42, 44. The openings 54 are of such a size and quantity that the water thus enters the cylinders 42 25 and 44 in a spray which, meeting the hot gases coming from the end of retort 18 and from the furnace receptacle 26, absorbs the chlorin gas contained therein and forms hydrochloric acid, which drops down into the 30 collecting tank 62, from which it is drawn into jars or other receptacles 64 by means of the valves 66, or the like. The products of combustion other than the hydrochloric acid, pass out of the passageway 46.

35 The use of the lugs 52 and downwardly tapering holes 54 is important in that as long as there is water on top of the plate 48 and above the tops of the adjacent lugs 52, no heated gas will pass upward through the 40 passageways 54, into the open air. This is important when water is not passing from pipes 56 through openings 54, thereby filling them, as otherwise there would be an escape into the open air of considerable quantities 45 of the gaseous products delivered from the retorts 18 and 26.

As often as all of the liquid "pickle" 50 within the retort (or retorts) 18 is driven off and the remaining product has, therefore, 55 become thoroughly dried, the retort is emptied by the insertion of a scraper in the left hand end (the cover 22 being removed for the purpose) and new, solid, wet substance is placed in the retort.

55 It will be seen from the foregoing that the same fire which is needed to evaporate the "pickle" solution within the hearth 26, dries out the solid paint material within the retorts 18 and that the gaseous products of 60 both operations pass through to the washing cylinders 42 and 44 where all of the hydrochloric acid is recovered in solution.

It will be noticed that that portion of the discharge pipe or passageway heretofore de- 65 scribed, represented by the numeral 31, is

placed under ground (represented by the line 70). In practice, it is most satisfactory to have the length of this pipe 31 about fifty feet, as by so doing the gases passing through it are slightly cooled and brought 70 to a more suitable condition for action by the water delivered through nozzles 56. This pipe 31 is supplied with a man hole 72, through which it may be cleaned if necessary.

75 For the sake of clearness, the words "retort" and "hearth" have been used in the specification and claims but these words are not to be understood as limiting applicant to the particular forms and shapes of these devices shown in the drawings.

I claim:

1. In apparatus for treating waste hydrochloric acid pickle liquor, in combination with a hearth adapted to contain a liquid, 85 and fire grates arranged so that flames from material placed thereon will pass over said hearth, a retort, adapted to contain wet solid material placed immediately adjacent to said fire grates so that said flames contact 90 with said retort before passing to the hearth and that vapor driven off from the solid material within the retort passes with said flames over the hearth and a recovery chamber into which the resulting gaseous products pass and means providing a water spray within said chamber for the purposes set forth.

2. In apparatus for treating waste hydrochloric acid pickle liquor, in combination 100 with a hearth adapted to contain a liquid and fire grates arranged so that flames from material placed thereon will pass over said receptacle; a retort open at both ends for the passage of air therethrough adapted to 105 contain wet solid material, said retort being placed immediately adjacent to said fire grate so that said flames contact with said retort before passing to the hearth and that vapor driven off from the solid material 110 within the retort mixes with the air passing therethrough and passes with said flames over the hearth and means for collecting the hydrochloric acid from the resulting gaseous products, for the purposes set forth. 115

3. In apparatus for treating waste hydrochloric acid pickle liquor, in combination with a hearth adapted to contain a liquid and fire grates arranged so that flames from material placed thereon will pass over said hearth, a retort open at both ends for the passage of air therethrough adapted to contain wet solid material, said retort being placed immediately adjacent to said fire grate so that said flames contact with said retort before passing to the hearth, and that vapor driven off from the solid material within said retort mixes with air passing therethrough and passes with said flames over the hearth, and means for regulating 120 125 130 132

the volume of air admitted to and through said retort, for the purposes set forth.

4. In apparatus for treating waste hydrochloric acid pickle liquor, in combination with a hearth adapted to contain a liquid, and fire grates arranged so that flames from material placed thereon will pass over said hearth; a retort adapted to contain wet solid material placed immediately adjacent to said fire grates so that said flames contact with said retort before passing to the hearth that vapor driven off from said solid material within the retort passes with said flames over the hearth, and means for regu-

lating the size of an opening in the retort 15 through which air may be admitted past the solid material therein to the interior of the furnace, and through which solid material may be inserted and removed during the operation of the device without disturbing 20 said operation.

In witness whereof, I have hereunto subscribed my name in the presence of two witnesses.

GUSTAF H. STARCK.
